Primary Examiner — Ruth McInroy(74) *Attorney, Agent, or Firm* — Grossman Tucker
Perreault & Pfleger, PLLC(57) **CLAIM**

The ornamental design of a vacuum cleaner, as shown and described.

DESCRIPTION

FIG. 1 is a top perspective view of a vacuum cleaner showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines are included for the purpose of illustrating the unclaimed portions of the article and form no part of the claim.

1 Claim, 6 Drawing Sheets(56)
